EX

OR D 19,130

D19130

UNITED STATES PATENT OFFICE.

TIMOTHY J. COLLINS, OF TOLEDO, OHIO, ASSIGNOR TO T. J. COLLINS & CO.,
OF SAME PLACE.

DESIGN FOR A DRESSING-CASE.

SPECIFICATION forming part of Design No. 19,130, dated June 4, 1889.

Application filed February 25, 1889. Serial No. 301,121. Term of patent 3½ years.

To all whom it may concern:

Be it known that I, TIMOTHY J. COLLINS, a citizen of the United States, residing at Toledo, in the county of Lucas and State of Ohio, have invented and produced a new and original Design in Dressing-Cases; and I do hereby declare that the following is a full, clear, and exact description of the invention, which will enable others skilled in the art to which it applies to make and use the same, reference being had to the accompanying drawing, and to the letters of reference marked thereon, which form part of this specification.

The drawing represents a front elevation of my newly-designed dressing-case.

The leading feature of the design consists in a dressing-table A, having a base comprising the back G and rectangular supports B, (one on each side,) the supports being closed by lower panel-doors E and upper doors F, each door F being ornamented by a grotesque face carved in relief. At the rear of the supports B is a paneled back G, and upon the top of each support is a shelf H, and centrally of the same is a top I, supported at a sufficient height from the side shelves to accommodate drawers J. Upon the base-supports is secured a frame-work K, into which is secured a mir-

ror L, and from the frame-work of the mirror is extended outwardly and at an angle to the sides and top of the mirror-frame a frame-work M, the frame M being at an acute angle to the outer edges of frame K, forming V-shaped corner-spaces N, which are provided with correspondingly-shaped shelves O, having ornamental outer edges of the form of a segment of a circle. The top portion of the frame-work M is ornamented with projecting standards having ornamental top portions and an ornamental cross-piece Q. In the obtuse-angled inner sides and top of the frame-work M is a series of mirrors P, surrounding the mirror L upon three sides, thereby giving a highly-ornamental appearance to the whole design.

What I claim is—

The design for a dressing-case having the shape and ornamentation herein shown and described.

In testimony that I claim the foregoing as my own I hereby affix my signature in presence of two witnesses.

TIMOTHY J. COLLINS.

Witnesses:

WILLIAM WEBSTER,
CARROLL J. WEBSTER.
